UNITED STATES PATENT OFFICE.

RAY BURDETTE PALMER, OF NORWICH, NEW YORK.

IRONING-BOARD.

1,156,805.

Specification of Letters Patent. Patented Oct. 12, 1915.

Application filed December 12, 1914. Serial No. 876,799.

To all whom it may concern:

Be it known that I, RAY B. PALMER, a citizen of the United States, and a resident of Norwich, in the county of Chenango and 5 State of New York, have invented a new and Improved Ironing-Board, of which the following is a full, clear, and exact description.

An object of my invention is to provide 10 an ironing board having folding supports arranged to firmly sustain the ironing board, while permitting of skirts and other long articles being readily adjusted to the board.

15 A further object of the invention is to provide folding supports that will permit the board to be readily adjusted for varying the height of the board, and will sustain the latter in a level position at the adjusted height.

The invention will be particularly explained in the specific description following.

Reference is had to the accompanying drawings forming part of this specification, 25 in which similar characters of reference indicate corresponding parts in all the views, and in which:

Figure 1 is a side elevation of an ironing board embodying my invention, showing the 30 same set up for use; Fig. 2 is an inverted plan view of the board with the supporting elements folded; and Fig. 3 is a perspective view of a board set up for use.

In constructing a practical embodiment 35 of my invention in accordance with the illustrated example, a board 10 of the usual shape and desired size has pivoted thereto near one end, a pair of folding legs 11, the pivotal connection of the legs being effected 40 in the illustrated example, by mounting the same on the ends of a cleat 12, secured transversely to the board at the underside by screws 13, or the like.

In addition to the legs 11 attached to the 45 board, I provide additional legs 14 indirectly connected with the board. Bars 15 are pivotally mounted at the upper end preferably mounted on the ends of the cleat 12. The lower ends of the bars 15 are pivotally 50 connected to the legs 14 between the upper and lower ends of the latter. Pivotal connection between the bars 15 and the legs 14 may be effected by a cross bar 16 extending through the said legs and elements. Strut 55 elements 17 in the form of spaced side bars are pivotally mounted at their lower ends

on the cross bar 16, and therefore pivotally connected with the bars 15 and with the legs 14. At the upper ends the strut elements 17 are provided with a cross bar 18 60 which is adapted to rockably and detachably engage the board 10, at the underside, at a point distant from the pivotal center of the legs 11 and bars 15; in the present instance alined bearing blocks 19 are secured 65 to the underside of the bar to receive the cross bar 18, which is round in cross section, at the points where it engages said bearing blocks.

Provision is made for adjustably supporting the upper ends of the legs 14 on the legs 11 between the upper and lower ends of the latter legs. For the purpose mentioned said legs 11 are provided with a cross bar 20, and in the legs 14 adjacent to the upper end 75 a longitudinal series of notches 21 are formed at the underside, any one of which may engage bar 20 according to the adjustment required. The legs 14 may be joined by a cross bar 22 at the upper end, and similarly to strengthen the legs 11, the latter may have a cross bar 23 near the upper end. 80

With the described construction it will be seen that when the board is set up for use, the legs 11 will be at an angle to the bars 15, and the said bars 15 will be at an angle to the strut elements 17. The legs 14 engage the floor at a point below the opposite end of the board from the legs 11, so that a broad supporting base is provided; also, it will be 85 seen that the legs 14 in effect constitute a lever, when the board is set up for use, since the imposed weight and the pressure of ironing make the point of engagement between the legs 14 and the cross bar 20 a fulcrum, 90 and the force exerted through the strut elements 17 will be exerted on the legs 14 at the pivoted point 16, and will be distributed through the bars 15. Similarly, the reaction 95 on the legs 14 will be sustained by the elements 15, 17.

The construction described permits of a rapid adjustment to vary the height of the ironing board by engaging the board 20 with different sets of notches 21 in the legs 14. 100

In order to fold the board, it is necessary only to disengage the legs 14 from the board 20 and disengage the cross bar 18 from the bearings 19, after which the several bars may be folded against the underside of the 110 board, as indicated in Fig. 2. In the folding movements, the members 17 swing on

the rod 16 as a center, into parallelism with the legs 14, and between the latter, and the members 15 and legs 11 will swing on the element 12 as a center. The legs 14 will 5 swing bodily with the members 15, and at the same time will rock on the rod 16.

Having thus described my invention, what I claim as new and desire to secure by Letters Patent, is:

- 10 1. An ironing board and supporting means therefor, said means comprising a pair of legs pivotally hung at their upper ends to the board near one end of the latter, bars pivotally hung at their upper ends, 15 said bars and said legs having a common pivotal center, a second pair of legs, strut elements, means pivotally connecting the said bars with the strut elements at their lower ends and with the second pair of legs 20 between the ends of the latter, means to detachably pivot the upper ends of the strut elements to the board at a point distant from the pivoting of the said bars, and means to 25 adjustably support the upper ends of the second pair of legs on the first pair of legs between the top and bottom of the latter.
2. An ironing board and supporting means therefor, the said supporting means comprising legs pivotally connected at their 30 upper ends with the board near one end of the latter, bars pivotally hung on the board near said end, strut elements detachably and pivotally engaging the board at a point distant from the pivoting of the said bars, 35 additional legs, means pivotally suspending the additional legs on the lower ends of the said bars and struts, and means to detachably support the upper ends of the additional legs on the first legs.
- 40 3. An ironing board and supporting

means therefor, said supporting means comprising a pair of legs, a transverse cleat on which said legs are pivoted at their upper ends, bars pivoted on said cleat and extending therefrom at an angle to the said legs, 45 strut elements, a transverse rod connecting the upper ends of the said strut elements, bearing means on the board distant from the cleat for detachably receiving the second transverse rod to permit the said strut elements to rock on or to be disengaged from 50 said bearing means, a transverse rod connecting the lower ends of the said bars and the lower ends of the said struts, and legs pivotally hung between the ends thereof on 55 the last mentioned transverse rod, the first legs having a cross bar between the top and bottom thereof, and the second legs having at the upper end series of notches to adjustably and detachably engage said cross bar. 60

4. An ironing board having legs pivotally connected at their upper ends with the board, additional legs, members pivotally connected at their upper ends with the board and pivotally connected at their lower ends 65 with the said additional legs between the ends of the latter, additional members pivotally connected at their lower ends with the additional legs and detachably engaging at their upper ends with the board, and means 70 to support the upper ends of the additional legs.

In testimony whereof I have signed my name to this specification in the presence of two subscribing witnesses.

RAY BURDETTE PALMER.
